UNITED STATES PATENT OFFICE

ALBERT C. FRIEDLUND, OF MINNEAPOLIS, MINNESOTA

DESIGN FOR A CONFECTIONERY ARTICLE

Application filed March 26, 1931. Serial No. 39,250. Term of patent 14 years.

To all whom it may concern:

Be it known that I, ALBERT C. FRIEDLUND, a citizen of the United States, residing at Minneapolis, in the county of Hennepin and State of Minnesota, have invented a new, original, and ornamental Design for a Confectionery Article, of which the following is a specification, reference being had to the accompanying drawings, forming part thereof, wherein:

Fig. 1 is a plan view of an article of confectionery embodying my design,

Fig. 2 is a side elevation, and

Fig. 3 is a rear perspective view of the same.

What is claimed is:—

The ornamental design for a confectionery article, substantially as shown.

ALBERT C. FRIEDLUND.
